SANCTUARY CANDLE LAMP

Thomas J. Muench and Oscar D. Guilfoil, Syracuse, N. Y., assignors to Muench-Kreuzer Candle Company Inc., Syracuse, N. Y., a corporation of New York

Application July 19, 1935, Serial No. 32,250

11 Claims. (Cl. 240—13)

This invention relates to candle lamps, or sanctuary lamps, and has for its object a candle lamp construction embodying a follower which will contribute toward a better and more even burning or consuming of the candle under hot weather conditions by allowing the candle to melt uniformly and form and maintain a uniform liquid pool at the upper end of the candle, and also at the same time avoid flooding or drowning of the flame, and under cold weather conditions, will keep the candle, particularly the outer portion thereof warm enough to melt, form and maintain the liquid pool and hence avoid burning of the candle down through the center with the peripheral portions remaining solid so that the flame becomes invisible. In other words, it has for its object a candle lamp which includes a follower in which the candle burns evenly under hot and cold weather conditions.

20 In candle lamps embodying followers, under some conditions, the follower, which rests on the upper edge of the candle, out of alignment with the candle or cocked relatively to the candle.

In this candle lamp, the follower acts as a follower during the initial or a predetermined consumption of the candle, and thereafter, is limited in its movement, as a follower, and forms a chimney permitting a liquid pool to form at the base of the flame throughout the area of the 30 end of the candle. Under warm weather conditions, with the shield removed, the pool after once forming remains substantially constant over the area of the burning end and does not increase to an extent to flood the flame. Under 35 cold weather conditions, a shield is used to confine sufficient heat around the sleeve or skirt of the follower to cause the liquid pool to form and remain uniform over the area of the burning end, the shield forming an air jacket, causing the pool 40 to be maintained over the area of the upper end of the candle and to avoid burning of the candle down through the center by the cooling of the peripheral area of the candle.

The invention consists in the novel features 45 and in the combinations and constructions hereinafter set forth and claimed.

In describing this invention, reference is had to the accompanying drawing in which like characters designate corresponding parts in all the 50 views.

Figure 1 is a longitudinal sectional view of a sanctuary candle lamp embodying this invention.

Figure 2 is a plan view of the candle receptacle.

This candle lamp comprises generally a suitable receptacle in which the candle is seated, a

follower resting on the upper end of the candle and having a skirt or sleeve enclosing the candle throughout the length of the candle and preferably extending into the receptacle, and means for limiting the movement of the follower, after an initial or predetermined amount of burning of the candle, say for a one-day period, also means, as an outer tubular transparent shield enclosing the follower and spaced apart therefrom forming a heated air jacket for heating the sleeve of the follower in colder weather sufficiently to keep the liquid pool substantially uniform over the area of the flame end of the candle, the shield being ventilated in order to maintain a sufficient air circulation to prevent the follower from becoming unduly warm and unduly heating and melting the candle.

1 designates the receptacle in the form of a cup, this being usually formed of glass, the receptacle being mounted in a suitable holder or support, as a cup-shaped part, 2, in which the receptacle is seated. As here shown, the receptacle 1 and support 2 are formed intermediate of their heights with outward deflected portions forming a shoulder at 3 from which the receptacle is suspended in the holder 2. The upper edge of the receptacle 1 usually overlaps the upper edge of the cup-shaped holder 2, as at 4. The support may be mounted on a suitable base or pedestal 5 or may be suspended by means of cords or chains connected to the upper end of strips or uprights 6 extending from the support 2 upwardly along the outside of the shield to be presently described. The upper ends of these uprights or strips 6 are usually secured together by means of a ring 7. Preferably, the holder 2 is imperforate and entirely encloses the receptacle 1 and insulates or shields it from the outer air, so that it is unaffected by variations in temperature of the outer air.

8 designates the candle which is seated in the receptacle 1, it having an axial reduced portion 9 at its lower end extending into a socket 10 in the receptacle and also suitable notches in its lower end which fit over lugs 11 in the receptacle.

12 designates a follower having a contracted portion at its upper end providing a shoulder at 13 which rests on the upper end of the candle 8, the follower terminating at its upper end in the chimney 14. The follower, in addition, includes a sleeve or skirt 15 entirely enclosing the portion of the candle which projects above the receptacle 1 and also preferably extends part way into the receptacle, the follower, or, at least the sleeve thereof, being transparent.

During the initial burning of the candle, say for a period of one day, or of about one inch, the follower follows down with the candle, as the candle consumes, and thereafter, the follower is held stationary or held from following. As here shown, it comes to rest upon lugs or stops 16 which limit the movement thereof, when the outer shield is not used, these being located in the receptacle.

10 17 designates a transparent tubular shield enclosing the follower and the sleeve thereof and extending above the upper end of the follower, this communicating at its upper end with the outer air and also communicating at its lower end with the outer air, the shield being spaced apart from the sleeve or follower forming a heated air space 18 which is ventilated sufficiently to prevent undue heating and melting of the candle. The lower edge of the shield 17 is opposed to 20 the upper edge of the support or the upper edge of the receptacle 1. One of these opposing edges, usually the upper edge of the receptacle, is formed with projections or lugs 19 which serve to space the lower edge of the shield 17 from the upper 25 edge of the receptacle 1, thereby forming air inlets at 20.

Preferably, means are located near the upper end of the follower 12 or upper end of the air space 18 for limiting its movement after it has initially consumed a predetermined amount or as much as one inch for a candle of about three 30 inches in diameter, when the shield is being used. As here shown, the shield 17 and follower are formed with spaced apart shoulders. 21 designates an internal annular shoulder on the shield near the upper end thereof, and 22 a shoulder on the follower located to engage and rest on the shoulder 21 when the candle has been consumed a predetermined amount. The shoulder 22 is usually 35 the rim of the chimney 14, which rim is deflected outward. The shoulders 21, 22, when engaged, retard the circulation of air through the air space 18 and hence permit a greater temperature to develop than when the space is wide 40 open at its top. The shoulders 21, 22 also limit the movement of the follower to prevent it from seating at its lower end and becoming stuck in the wax at its lower end when the shield is used.

Under moderate temperature conditions, the 50 lamp is used without the shield and under cold temperature conditions, the shield is used.

In operation, during the initial burning of the candle, say for a period of one day, the follower follows down as the candle burns. During this 55 operation, there is little liability of the liquid forming excessively to flood the flame. Thereafter, the movement of the follower is limited by the lower edge of the sleeve of the follower engaging the stops 16 so that thereafter the follower 60 acts as a chimney, and the air space 18 is closed at its top by the shoulder 22 engaging the shoulder 21. Under warmer temperatures, the shield is removed and the candle is cooled sufficiently to avoid melting to the extent that 65 the flame will be flooded. Under cold temperature conditions, the shield forms a ventilated heated air space which maintains a uniform heating of the candle sufficient to maintain the liquid pool uniformly and prevent burning of the 70 candle down through the center only, although the ventilation is slow or greatly retarded when the shoulder 22 engages the shoulder 21.

What we claim is:—

1. In a candle lamp, a receptacle, a candle 75 mounted at its lower end in the receptacle, a

follower having a shoulder resting on the upper end of the candle, and also having as a part thereof a transparent sleeve enclosing the candle and normally extending throughout the length of the full-sized candle and into the receptacle, and a stop for limiting the movement of the follower, as the candle consumes, whereby the follower and its sleeve act as a chimney after the follower is limited in its movement. 5

2. A candle lamp comprising a receptacle in 10 which the lower end of the candle is seated, a follower resting on the upper end of the candle and having a transparent sleeve enclosing the candle, extending at its lower end into the receptacle with the greater part thereof extending 15 out of the receptacle and of such length as to enclose a full length candle, and during the initial burning of the candle being capable of following the candle, as the candle consumes, and means for limiting the movement of the follower 20 as the candle consumes a predetermined amount, whereby the follower forms a transparent chimney. 25

3. In a candle lamp, a receptacle in which the lower end of the candle is seated, a transparent sleeve enclosing the candle substantially the length thereof above the receptacle and an outer tubular transparent shield enclosing the sleeve and spaced apart therefrom forming an air jacket, the lower edge of the shield being spaced 30 apart from, and opposed to the upper edge of the receptacle, and thereby forming an air gap between the lower end of the shield and the upper edge of the receptacle. 35

4. In a candle lamp, a receptacle in which the lower end of the candle is seated, a transparent sleeve enclosing the candle substantially the length thereof above the receptacle and an outer tubular transparent shield enclosing the sleeve and spaced apart therefrom forming an air jacket, the lower edge of the shield being spaced 40 apart from; and opposed to the upper edge of the receptacle, and thereby forming an air gap between the lower end of the shield and the upper edge of the receptacle, the shield being open to 45 the atmosphere at its upper end.

5. In a candle lamp, a receptacle, a candle mounted at its lower end in the receptacle, a follower having a shoulder resting on the upper end of the candle, and also having as a part thereof a transparent sleeve enclosing the candle and extending into the receptacle, a stop for limiting the movement of the follower, as the candle consumes, whereby the follower and its sleeve act as a chimney after the follower is limited in its movement, and an outer transparent shield enclosing the follower and spaced therefrom forming an air jacket, the shield being open to the atmosphere at its upper end and also being open to the atmosphere at its lower end. 55

6. In a sanctuary lamp, a receptacle in which the lower end of the candle is seated, a suitable support for the receptacle, a follower resting on the upper end of the candle and having a sleeve enclosing the candle and terminating adjacent the receptacle, means for limiting the movement of the follower, whereby after the initial burning of the candle, the follower is held from movement, a transparent tubular shield enclosing the follower and spaced therefrom forming an annular jacket around the follower and its sleeve, the shield being open to the atmosphere at its upper end and having its lower end spaced from the upper edge of the receptacle, thereby forming air 70 passages. 75

7. In a candle lamp, a receptacle in which the lower end of the candle is seated, transparent means enclosing the candle, a tubular sleeve enclosing said transparent means and spaced apart therefrom forming an air jacket, the shield communicating with the outer air at its upper end and having its lower edge opposed to the upper edge of the receptacle, one of the opposing edges being formed with projections thereon for spacing the lower edge of the shield from the upper edge of the receptacle and thereby forming air passages.

8. In a candle lamp, a receptacle in which the lower end of the candle is seated, a suitable support for the receptacle, a follower resting on the upper end of the candle and having a transparent sleeve of such length as to enclose a full length candle, the sleeve terminating near the receptacle, and means for limiting the movement of the follower after a predetermined consumption of the candle, whereby the follower constitutes the transparent chimney.

9. In a candle lamp, a receptacle in which the lower end of the candle is seated, a suitable support for the receptacle, a follower resting on the upper end of the candle and having a transparent sleeve enclosing the candle and terminating near the receptacle, means for limiting the movement of the follower after a predetermined consumption of the candle, whereby the follower constitutes the transparent chimney, and a tubular transparent shield enclosing the follower and its sleeve and spaced apart therefrom forming an air

jacket, the shield communicating with the outer air at its upper end and having its lower edge opposed to the upper edge of the receptacle, one of the opposing edges being formed with projections for holding the shield with the lower edge spaced from the upper edge of the receptacle.

10. In a candle lamp, a receptacle in which the lower end of the candle is seated, a transparent sleeve enclosing the candle substantially the length thereof above the receptacle and an outer tubular transparent shield enclosing the sleeve and spaced apart therefrom forming an air jacket, the lower edge of the shield being spaced apart from the lower edge of the receptacle, the follower and the shield having normally spaced shoulders located in the upper portion of the air space for engaging and restricting the outlet of air from the air jacket when the candle has consumed a predetermined amount.

11. In a candle lamp, a receptacle in which the lower end of the candle is seated, a transparent sleeve enclosing the candle substantially the length thereof above the receptacle and an outer tubular transparent shield enclosing the sleeve and spaced apart therefrom forming an air jacket, the follower and the shield having respectively external and internal spaced apart annular shoulders in the upper portion of the jacket for engagement when the candle has initially consumed a predetermined amount.
